[57] CLAIM

The ornamental design for intravenous metering cassette, as shown and described.

DESCRIPTION

FIG. 1 is a top plan view of an intravenous metering cassette showing my new design;
FIG. 2 is a front elevation thereof;
FIG. 3 is a bottom plan view thereof;
FIG. 4 is a rear elevation thereof;
FIG. 5 is a left end elevation thereof;
FIG. 6 is a right end elevation thereof;
FIG. 7 is a front perspective view thereof on an enlarged scale; and
FIG. 8 is a fragmentary cross-sectional view taken along line 8—8 of FIG. 7.

FIG. 1

FIG. 2

FIG. 3

FIG. 4

FIG. 5

FIG. 6

FIG. 7

FIG. 8
